UNITED STATES PATENT OFFICE.

WILLIAM W. WADSWORTH, OF TREMONTON, UTAH.

CAN POLISHING AND SCOURING MACHINE.

Application filed August 26, 1926. Serial No. 131,697.

This invention relates to certain new and useful improvements in can polishing and scouring machines and has for its primary object to polish and scour the ends of cans 5 after being packed and prior to the pasting of the labels upon the cans so that the opposite ends of the cans will have a polished and finished appearance.

Another object of the invention is to provide a machine of the above type wherein there is provided an inclined guideway through which the cans roll to a pair of spaced scouring and polishing brushes with means for causing the brushes engaging the 10 opposite ends of the cans to rotate in reverse directions, means to move the brush elements toward and away from each other and a cam operated device for elevating the cans from the guideway and delivering the 15 same into an inclined discharge chute.

With the above and other general objects in view that will become apparent as the nature of the invention is better understood, the same consists in the novel form, 20 combination and arrangement of parts hereinafter more fully described, shown in the accompanying drawings and claimed.

In the accompanying drawings wherein like reference characters indicate corresponding parts throughout the several 25 views.

Figure 1 is a top plan view of a can scouring and polishing machine constructed in accordance with the present invention 30 showing the tensioned axially shiftable brushes for polishing the can ends, the receiving and delivery chutes for the cans and the operating mechanism for the brushes;

Figure 2 is a side elevational view of the 35 machine showing the cam mechanism for operating the can ejecting device;

Figure 3 is a vertical longitudinal sectional view taken on line 3-3 of Figure 1 showing the motor drive, the can ejecting 40 mechanism and the operating devices for the brush element;

Figure 4 is a fragmentary side elevational view, partly in section showing the receiving and delivery chutes of the machine with the can ejecting plunger and operating cam associated therewith; and

Figure 5 is a vertical cross sectional view 45 taken on line 5-5 of Figure 2 showing the cam operated arms that carry the brush element for moving the latter toward and away from the can ends.

The cam scouring and polishing machine being designed for cleaning the ends of cans prior to the application of the usual labels that completely encircle the side 60 walls of the cans, comprises a frame structure having corner legs 1 connected at their upper ends by side bars 2 with cross bars 3 and 4 extending between the upper sides of the side bars 2. The legs at opposite 65 sides of the machine frame are further braced by the cross platform 5 while the legs at each side of the frame are connected intermediate their ends by side rails 6.

A driven shaft 7 is journaled at its ends 70 in bearings 8 carried by the upper sides of the side rails 6 and said shaft 7 is driven from a shaft 12, which has a pulley 9 fixed thereto as shown in Figures 1 and 3, and that has a belt connection 10 with the shaft 75 of the motor 11 that is supported upon the platform 5. The shaft 12 is journaled at its opposite ends in the upper ends of the corner legs at the end of the frame structure opposite the platform 5 and said shaft 80 12 has a pulley 13 fixed thereto that has a belt connection 14 with the further pulley 15 fixed to the shaft 7. The pulleys 14 and 15 are fixed to the shafts 12 and 7 adjacent 85 similar ends thereof, and through the medium of the belt connections, the motor 11 effects rotation of said shafts. The shaft 12 has driving connections with brush elements to be presently described. Receiving and delivery chutes 16 and 17 respectively are supported upon the cross bars 3 and 4 as shown in Figures 1 and 3, the receiving end of the delivery chute being at an elevation slightly higher than the lower end of the receiving chute to act as an 90 abutment or temporary stop for the cans C as will be evident from an inspection of Figures 3 and 4. Each of the chutes 16 and 17 has upstanding side walls 18 and 19 respectively, the side walls 18 of the 100 chute 16 being broken away at the ends thereof adjacent the receiving end of the chute 17 to provide a clearance for movement of can scouring and polishing brushes as shown in Figures 1 and 3.

The scouring and polishing brushes 31 arranged in opposed relation as shown in Figures 1 and 5 are each mounted upon a shaft 31 that is both rotatable and longitudinally shiftable in the bearing 22 carried by the 105 upper side of the side bar 2. In order to hold the two brushes 20 normally separated

from each other, there is provided a coiled spring 23 enclosing each shaft 21 between the adjacent bearing 22 and a pulley 24 at the outer end of the shaft, and each shaft 21 is rotated by the belt connection 25 extending from the pulley 24 and inclosing a pulley 26 upon the adjacent projecting end of the shaft 12, the belt 25^a being crossed to cause the shafts 21 to rotate in opposite directions to effect a more thorough scouring and polishing of the can ends. The devices for moving the brush elements 20 toward each other for contact with the can ends includes a pair of levers 27 that are pivotally mounted as at 28 upon the cross bar 29 that extends between the side bars 2 of the frame structure with a bearing 30 at the upper end of each lever through which the shaft 21 rotatably extends. The inner end of each shaft 21 has a brush head 31 detachably connected thereto, the brush head 31 being engaged by a coil spring 32 interposed between the brush head and bearings 30 of the lever 27 with the washer 33 interposed between the bearing 30 and adjacent end of the spring 32. The spring 32 and bearing 30 provides lost motion when the lever 27 is operated to axially shift the shaft 21 against the tension of the spring 23 to relieve undue pressure on the opposite ends of the cans C.

The device for simultaneously operating the levers 27 includes a cam wheel 34, secured to the shaft 7 inwardly of pulley 15, having lateral cam faces 35 extending from opposite sides thereof at the peripheral edge as shown in Figures 3 and 5 for a portion of the circumference of the cam wheel for engagement with rollers 36 carried by the lower ends of the levers 27 for pivotally moving said levers to axially shift the shafts 21 in the manner above described.

When the cans C have had their ends polished by the brush elements 31, the polished can is elevated from the lower end of the receiving chute 16 and deposited upon the receiving end of the delivery chute 17 for passage from the machine, the devices for accomplishing this purpose comprising a lever bar 37 pivoted at one end upon the shaft 12 with the side thereof engaging the periphery of the cam wheel 34 and periodically elevated by the cam wheel when the peripheral cam portion 38 of the cam wheel moves into contact with the lever bar 37 as shown in Figure 4. A vertically moving plunger rod 39 is pivotally connected at its lower end as at 40 to the free end of the lever bar 37 with the upper end of the plunger rod moving through an opening in the chute 16 for elevating an adjacent can as shown in Figure 4. The lever bar 37 is retained in its lowered positive operatively engaged with the peripheral cam surface of the cam wheel 34 by the spring 41 having one end thereof connected at 42 to the free end of the lever bar

37 while the other end of the spring is anchored as at 43 to the frame platform 5.

From the above detailed description of the device, it is believed that the construction and operation thereof will at once be understood, it being noted that the motor 11 is employed for rotating the shaft 12 and through the belt and pulley connections, the shaft 7 and shafts 21 that carry the brush elements 31. The belt 25^a being crossed, the brush elements 31 are rotated in opposite directions while the cam wheel 34 rotating with the shaft 7 operates the levers 27 which cause movement of the brushes toward and away from the cans C passing through the machine. At proper intervals, the plunger rod 39 is elevated when the brush elements are separated to place a polished can in the delivery chute 17. The cam portions 35 and 38 upon the cam wheel 34 are so related to cause the plunger rod 39 to be lowered during operative engagement of the brush elements 31 with the can ends and said plunger rod 39 to be elevated when the brush elements are outwardly shifted in spaced relation to the cans.

While there is herein shown and described the preferred embodiment of the present invention, it is, nevertheless, to be understood that minor changes may be made therein without departing from the spirit and scope of the invention as claimed.

Having thus described my invention, I claim:

1. A can scouring and polishing machine comprising means for feeding cans into the machine, ejecting means for the cans, means for scouring and polishing the can ends and means for alternately operating the ejecting and polishing means.

2. A machine for polishing can ends comprising means for feeding cans into the machine, means for polishing the ends of cans movable toward and away from the cans, means for ejecting the cans from the machine after polishing and means for alternately operating the polishing and ejecting means.

3. A machine for polishing can ends comprising means for feeding cans into the machine, means for polishing the ends of cans movable toward and away from the cans, means for ejecting the cans from the machine after polishing and means for alternately operating the polishing and ejecting means, said feeding means including receiving and delivery chutes with the receiving end of the delivery chute constituting an abutment for the cans.

4. A machine for polishing can ends comprising means for feeding cans into the machine, means for polishing the ends of cans movable toward and away from the cans, means for ejecting the cans from the machine after polishing and means for alter-

nately operating the polishing and ejecting means, said polishing means including alined rotatable and axially movable shafts, brush elements on the adjacent ends of the shafts, and springs for normally holding the brush elements separated.

5. A machine for polishing can ends comprising means for feeding cans into the machine, means for polishing the ends of cans movable toward and away from the cans, means for ejecting the cans from the machine after polishing and means for alternately operating the polishing and ejecting means, said polishing means including alined rotatable and axially movable shafts, brush elements on the adjacent ends of the shafts, springs normally holding the brush elements separated, and springs associated with the brush elements for equalizing pressure of the brushes on the can ends.

6. A machine for polishing can ends comprising means for feeding cans into the machine, means for polishing the ends of cans movable toward and away from the cans, means for ejecting the cans from the machine after polishing and means for alternately operating the polishing and ejecting means, said ejecting means comprising a plunger rod for elevating a can during ejecting movement thereof from the machine.

7. A machine for polishing can ends comprising means for feeding cans into the machine, means for polishing the ends of cans movable toward and away from the cans, means for ejecting the cans from the machine after polishing and means for alternately operating the polishing and ejecting means, said feeding means including receiving and delivery chutes with the receiving end of the delivery chute constituting an abutment for the cans, said polishing means including alined rotatable and axially movable shafts, a brush element on the adjacent ends of the shafts, and springs for normally holding the brush elements separated.

8. A machine for polishing can ends comprising means for feeding cans into the machine, means for polishing the ends of cans movable toward and away from the cans, means for ejecting the cans from the machine after polishing and means for alternately operating the polishing and ejecting means, said polishing means including alined ro-

tatable and axially movable shafts, a brush element on the adjacent ends of the shafts, 55 springs for normally holding the brush elements separated, and springs associated with the brush elements for equalizing pressure of the brushes on the can ends.

9. A machine for polishing can ends comprising receiving and delivery chutes for cans, a pair of reversely rotatable brush elements movable toward and away from each other for contact with can ends, an ejector for placing a polished can on to the delivery 60 chute, a pair of levers for moving the brush elements, and a unitary instrumentality associated with the ejector and levers for alternate operation thereof.

10. A machine for polishing can ends comprising receiving and delivery chutes for cans, a pair of reversely rotatable brush elements movable toward and away from each other for contact with can ends, an ejector for placing a polished can on to the delivery 65 chute, a pair of levers for moving the brush elements, and a unitary instrumentality associated with the ejector and levers for alternate operation thereof.

11. A machine for polishing can ends comprising receiving and delivery chutes for cans, a pair of reversely rotatable brush elements movable toward and away from each other for contact with can ends, an ejector for placing a polished can on to the delivery 70 chute, a pair of levers for moving the brush elements, and a can wheel having lateral cam portions engaging the levers and a peripheral cam portion engaging the ejector.

12. A machine for polishing can ends comprising receiving and delivery chutes for cans, a pair of reversely rotatable brush elements movable toward and away from each other for contact with can ends, an ejector for placing a polished can on the delivery 75 chute, a pair of levers for moving the brush elements, and a cam wheel having lateral cam portions engaging the levers and a peripheral cam portion engaging the ejector, the lateral and peripheral cam portions being circumferentially spaced to effect alternate operation of the polishing and ejecting means.

In testimony whereof I affix my signature.

WILLIAM W. WADSWORTH.
